FRANK W. MERRICK, OF BOSTON, MASSACHUSETTS

SEWING MACHINE AND THE LIKE

Application filed April 14, 1925. Serial No. 23,056.

The invention has relation to the class of mechanisms comprising those which are employed for the actuation of the work-penetrating tools of sewing machines, known commonly as needle-motions and awl-motions, and those employed for the actuation of other tools having the like reciprocating movements in different machines.

The invention comprises improved mechanisms of the said class, incorporating principles providing for transmission of power to the tool in mechanically advantageous manner from a cam or other rotating movement-initiating element; providing also for production of a dwell or dwells of relatively prolonged duration at desired points in the tool-movement, without any special "dwell" or dwell-formation of the movement-initiating element itself, for example the actuating cam in case the movement is due to the action of a cam; and providing further for absorbing the shock which is incident to a change of direction in the movement of the tool, at the end of the stroke of the tool in a given direction, so as to save the cam or other movement-initiating element, and the parts engaging therewith, from wear and strain incident to such change of direction.

Certain specific phases of the invention consist in novel and improved awl-actuating and needle-actuating mechanisms for sewing machines.

The drawings show embodiments of the features of the invention in mechanisms operatively combined with the curved awl and needle of a curved needle sewing machine for the actuation of the said curved awl and needle.

Fig. 1 of the drawings is a side elevation illustrating the curved awl and awl-actuating mechanisms, with the awl retracted.

Fig. 2 is a side elevation illustrating the awl in the advanced position corresponding with penetration of the work thereby.

Fig. 3 is a plan view illustrating the parts in the positions in which they are illustrated in Fig. 2.

Fig. 4 is a side elevation illustrating the curved needle and needle-actuating mechanism, with the needle retracted.

Fig. 5 is a plan view illustrating the parts in the positions in which they are illustrated in Fig. 4.

Fig. 6 is a side elevation illustrating the needle in the advanced position corresponding with penetration of the work thereby.

The awl is marked 1 in Figs. 1, 2 and 3, and the needle is marked 2 in Figs. 4, 5 and 6, an awl-carrier 11 and awl-guard 12 being shown in Figs. 1, 2 and 3 arranged to swing around the center 3, and a needle-carrier 21 and needle-guard 22 being shown in Figs. 4, 5 and 6, arranged to swing around said center 3 also. A portion of a work-table or support 4 is shown in the respective views. A rotating shaft is indicated at 5, and 6 is a cam-disk fixed upon said cam-shaft and having its periphery formed with helical teeth 7, thereby constituting a helical gear which in practice acts to transmit movement to a shuttle or loop-taker (not shown) to rotate the latter. At 8 is indicated a shaft supporting the primary levers 9 and 10 which are employed for transmitting movement to the awl and needle, the said primary levers being capable of turning independently of each other. The primary lever 9 is shown mounted upon shaft 8, in Figs. 1, 2 and 3, while the primary lever 10 is shown mounted thereon in Figs. 4, 5 and 6.

In the case of the illustrated embodiment of the invention, the cam-disk 6 has a cam-groove 61 formed in one side-face thereof, constituting a cam which is utilized for the actuation of the awl 1, and a cam-groove 62, shown by dotted lines, formed in the other face thereof, constituting a cam which is utilized for the actuation of the needle 2.

The awl-actuating train comprises the cam 61, the primary lever 9, a toggle-link 91, and a secondary lever 92 which is operatively engaged with awl-carrier 11. Toggle-link 91 connects one arm of lever 9 to one arm of lever 92. Preferably, and in accordance with one phase of the invention, the secondary lever 92 is engaged with the awl-carrier 11 by means of a link 93 connecting the second arm, 923, of lever 92 to the awl-carrier. Primary lever 9, mounted as aforesaid upon shaft 8, is provided with a cam-follower 611 working

in cam-groove 61. Secondary lever 92 in this instance is mounted upon cone-centers 921.

The needle-actuating train comprises the cam 62, the primary lever 10, a toggle-link 101, and a secondary lever 102 which is operatively engaged with needle-carrier 21. Toggle-link 101 connects one arm of lever 10 to one arm of lever 102. Preferably, and in accordance with one phase of the invention, 10 the secondary lever 102 is engaged with the needle-carrier by means of a link 103 connecting the second arm of lever 102 to the needle-carrier. Primary lever 10, mounted as aforesaid upon shaft 8, is provided with a 15 cam-follower 621 working in cam-groove 62. Secondary lever 102 in this instance is mounted upon cone-centers 121.

The awl-actuating cam 61 is designed to move the lever 9 and associated parts into the 20 positions shown in Fig. 1, in which the awl-carrier and awl are retracted, with the awl clear of the position that is occupied by the material operated upon when the said material rests on the work-table or support 4, and 25 to move the levers 9, 92, and links, subsequently into the positions shown in Figs. 2 and 3 to actuate the awl-carrier and awl into the position occupied in Figs. 2 and 3 in which position the awl penetrates the said 30 material in case the latter is present upon the work-table or support.

As the primary awl-actuating lever 9 moves in the direction indicated by the arrow in Fig. 1, toward the position shown in Fig. 2, its forward arm 901 acts through toggle-link 91 to push the rear arm of secondary lever 92 downward in the drawings, rocking the lever 92 so that the forward arm of such lever acts through link 93 to rock the awl-carrier and awl from their position in Fig. 1 to their position in Figs. 2 and 3. In this movement of arm 901 the point of connection *x* between such arm and one end of toggle-link 91 is carried toward a straight line extending from the axis of supporting shaft 8 to the point of connection *y* between the other end of the toggle-link and the rear arm 922 of lever 92. This straightening of the toggle constituted by lever-arm 901 and toggle-link 91 gives the advantageous action of the toggle in transmitting movement and power to lever 92 and the awl-carrier and awl. At the completion of the said movement the toggle-link and the connection-points *x* and *y* are approximately in the said straight line. Consequently, strain incident to the forcing of the awl through the material operated upon, and strain and shock resulting from the momentum of secondary lever 92 and the awl-carrier and awl at the moment of the termination of the penetrating movement of the awl, are transmitted along the said straight line to the supporting shaft 8 and absorbed by the latter and its bearings, without reaching cam 61 through the power-receiving arm of the

lever 9 and the cam-follower. This relieves the cam from the shock and from the action which in the case of prior mechanisms causes excessive wear and deformation of the cam at one point. Preferably the construction and arrangement are such that the link 93, also, is caused to operate as a toggle-link, through being carried into the relations shown in Fig. 2 as the parts are actuated to cause the awl to penetrate the material operated upon, whereby the point of connection *m* between one end of the link and the transmitting arm 923 of secondary lever 92 is brought into straight line with the center on which lever 92 turns and the point of connection *n* between the other end of the link and the awl-carrier. This adds the advantages of the toggle-action between the lever 92 and the awl-carrier, and in addition causes strains or shock at and near the completion of the penetrating movement of the awl to be transmitted to the center of lever 92 and be absorbed by the supporting bearings.

Both of the toggles embodied in the mechanism shown in Figs. 1, 2 and 3 are straightened at the same time. Consequently, the dwells of the two toggles occur at the same time, and the conjoint effect thereof is secured. The action gives a dwell in the actual movement of the awl-carrier and awl, continuing during the feed movement, such dwell being secured without any special dwell-formation of the cam 61. Through a considerable portion of the action which straightens and bends the toggles again the awl remains motionless. The conjoint action of the two toggles in bending gives a quick withdrawal movement of the awl which it would not be practicable to produce by means of a special shaping of the cam, alone. The absorption of strain and shock by the lever-supports allows the cam-actuated movement to be operated at a much higher rate of speed than would otherwise be practicable.

The needle-actuating cam 62 is designed to move lever 10 and the associated parts into the positions shown in Figs. 4 and 5, in which the needle-carrier and needle are retracted, with the needle clear of the position that is occupied by the material operated upon when the said material rests upon the work-table or support 4, and subsequently to move the levers 10, 102, and links, into the positions shown in Fig. 6, to actuate the needle-carrier 21 and needle into the position occupied in Fig. 6, in which position the needle penetrates the said material in case the latter is present upon the work-table or support.

As the primary needle-actuating lever 10 moves in the direction indicated by the arrow in Fig. 4, toward the position shown in Fig. 6, its forward arm 100 acts through toggle-link 101 to push the rear arm of secondary lever 102 forward, rocking the lever 102 so

that the forward arm of such lever acts through link 103 to rock the needle-carrier and needle from their position in Figs. 4 and 5, to their position in Fig. 6. In this movement of arm 100 the point of connection *c* between such arm and one end of link 101 is carried toward a straight line extending from the axis of supporting shaft 8 to the point of connection *d* between the other end of the toggle-link and the rear arm of lever 102. This straightening of the toggle constituted by lever-arm 100 and toggle-link 101 gives the same results in the case of the needle-actuating mechanism as in the case of the toggle of the awl-actuating mechanism, that is to say in respect of producing a dwell of the needle in the projected position of the latter, and in respect of causing the shock resulting from the termination of the thrusting movement of the needle to be taken up by shaft 8 and its bearings. The dwell of the needle in the projected position of the latter affords ample time for passing the needle-thread around the hook of the needle. Preferably, the construction and arrangement are such that the link 103, also, is caused to operate as a toggle-link, through being carried into the relations shown in Fig. 4 as the parts are actuated to cause the needle to withdraw from the material operated upon, whereby the point of connection *e* between one end of the link and the transmitting arm of secondary lever 102 is brought into approximately a straight line with the center on which lever 102 turns and the point of connection *f* between the other end of the link and the needle-carrier. This causes strain or shock at the completion of the withdrawing movement of the needle to be transmitted to the center of lever 102 and be absorbed by the supporting bearings.

The two toggles of the needle-actuating mechanism act alternately one acting in the thrusting movement of the needle and the other acting in the withdrawing movement. The former toggle acts at the extreme of the needle inserting action, with the needle through the material, as just stated producing a dwell of the needle and taking up shock resulting from the termination of the thrusting movement. The other toggle acts at the extreme of the needle withdrawing action to take up shock resulting from the termination of the said withdrawing action, as just stated.

The mechanisms thus far described are designed more particularly for employment in conjunction with a shuttle or loop-taker making a plurality of rotations per cycle of the machine, as for instance three rotations. Owing to this relative speed with which the shuttle or loop-taker rotates the inserting movements of awl and needle, and the withdrawals thereof, must take place within very small portions of the rotation of the shaft 5; in the present instance it has been contem-

plated effecting each of such movements within 110 degrees of one rotation of said shaft 5. This precludes the employment of any cams except those of comparatively simple and regular contour. The production of the required relative movements and dwells of the awl and needle through the employment of cams of comparatively simple and regular contour is made possible by means of the lever and toggle arrangements which have been described.

The ball-joints shown at points *m*, *n*, at the opposite ends of link 93 provide for the lateral movements of the awl-carrier and awl during the feed-movement.

What is claimed as the invention is:—

1. In mechanism such as specified, the combination with a tool, a rotating movement-initiating element, a primary lever actuated by said element, and a secondary lever, of a toggle-link connecting said levers together and cooperating with an arm of said primary lever as a toggle-link which as the mechanism completes the stroke of the tool approaches and assumes dwell-relations in which its effective length is substantially in line with the center on which said primary lever swings, and a toggle-link connecting the secondary lever with the tool and which at one extreme of the movements of the tool assumes relations in which its effective length is substantially in line with the center on which said secondary lever swings.

2. In mechanism of the class specified, the combination with a swinging curved work-penetrating tool, a rotating cam, a primary lever actuated by said cam, of a secondary lever working around an axis separate from that of the tool, and operatively connected with the latter by a link, and a second link connecting said levers together and cooperating with an arm of said primary lever as a toggle-link which as the mechanism completes the penetrating stroke of the tool approaches and assumes a relation in which its effective length is substantially in line with the center on which said primary lever swings, so as to transmit to the pivot of the primary lever instead of to the cam the burden imposed by said secondary lever in bringing the tool to rest.

3. In mechanism of the class specified, the combination with a work-penetrating tool, a rotating movement-initiating element, a primary lever actuated by said element, a secondary lever, a link connecting said levers together, and a link connecting the secondary lever with the tool, with the link first mentioned cooperating with an arm of the primary lever as a toggle-link which as the mechanism completes the penetrating stroke of the tool approaches and assumes a relation in which its effective length is substantially in line with the center on which said primary lever swings, and with the second link ar-

- ranged so that as the mechanism completes the stroke of the tool in one direction it approaches and assumes relations in which its effective length is substantially in line with the center on which the secondary lever swings.
4. In mechanism of the class specified, the combination with a work-penetrating tool, a rotating movement-initiating element, a primary lever actuated by said element, a secondary lever, a link connecting said levers together, and a link connecting the secondary lever with the tool, with the link first mentioned cooperating with an arm of the primary lever as a toggle-link which as the mechanism completes the penetrating stroke of the awl approaches and assumes a relation in which its effective length is substantially in line with the center on which said primary lever swings, and with the second link arranged so that as the mechanism completes the said penetrating stroke such link approaches and assumes relations in which its effective length is substantially in line with the center on which the secondary lever swings.
5. In mechanism of the class specified, the combination with a work-penetrating tool, a rotating movement-initiating element, a primary lever actuated by said element, a secondary lever, a link connecting said levers together, and a link connecting the secondary lever with the tool, with the link first mentioned cooperating with an arm of the primary lever as a toggle-link which as the mechanism completes the penetrating stroke of the tool approaches and assumes relations in which its effective length is substantially in line with the center on which said primary lever swings, and with the second link arranged so that as the mechanism completes the penetrating stroke it, the said second link, approaches and assumes relations in which its effective length is substantially in line with the center on which the secondary lever swings.
6. Awl-operating mechanism comprising, in combination with a swinging curved awl, a rotating movement-initiating element, a primary lever actuated by said element, and a secondary lever working around an axis separate from that of the awl and operatively connected with the latter, a link connecting said levers together and cooperating with an arm of said primary lever as a toggle-link which as the mechanism completes the penetrating stroke of the awl, approaches and assumes a dwell-relation in which its effective length is substantially in line with the center on which said primary lever swings.
7. Awl-operating mechanism comprising, in combination with an awl, a rotating movement-initiating element, a primary lever actuated by said element, a secondary lever, a link connecting said levers together, and a link connecting the secondary lever with the awl, with the link first mentioned cooperating with an arm of the primary lever as a toggle-link which as the mechanism completes the penetrating stroke of the awl approaches and assumes a relation in which its effective length is substantially in line with the center on which said primary lever swings.
8. Awl-operating mechanism comprising, in combination with a curved awl, a swinging awl-carrier, a rotating movement-initiating element, a primary lever actuated by said element, a secondary lever, a link connecting said levers together, and a link connecting the secondary lever with the awl-carrier, with the link first mentioned cooperating with an arm of the primary lever as a toggle-link which as the mechanism completes the penetrating stroke of the awl approaches and assumes a relation in which its effective length is substantially in line with the center on which said primary lever swings, and with the second link arranged so that as the mechanism completes the said penetrating stroke such link approaches and assumes relations in which its effective length is substantially in line with the center on which the secondary lever swings.
9. Needle-operating mechanism comprising, in combination with a swinging curved needle, a rotating cam, a primary lever actuated by said cam, and a secondary lever working around an axis separate from that of the needle and operatively connected with the latter, and a link connecting said levers together and cooperating with an arm of said primary lever as a toggle-link which as the mechanism completes the penetrating stroke of the needle approaches and assumes dwell-relations in which its effective length is substantially in line with the center on which said primary lever swings.
10. Needle-operating mechanism for a sewing machine comprising, in combination with a needle, a needle-carrier, a rotating cam, a primary lever actuated by said cam, a secondary lever, a link connecting the secondary lever with the needle-carrier, and a link connecting said levers together and cooperating with an arm of said primary lever as a toggle-link which as the mechanism completes the penetrating stroke of the needle approaches and assumes dwell-relations in which its effective length is substantially in line with the center on which said primary lever swings.
11. Needle-operating mechanism for a curved needle sewing machine comprising, in combination with a curved needle, a

- swinging needle-carrier, a rotating cam, a primary lever actuated by said cam, a secondary lever, a swinging link connecting the secondary lever with the needle-carrier, and
5 a link connecting said levers together and cooperating with an arm of said primary lever as a toggle-link which as the mechanism completes the penetrating stroke of the needle approaches and assumes dwell-relations
10 in which its effective length is substantially in line with the center on which said primary lever swings.
12. Needle-operating mechanism for a curved needle sewing machine comprising, in
15 combination with a curved needle, a swinging needle-carrier, a rotating movement-initiating element, a primary lever actuated by said element, and a secondary lever, a link connecting said levers together and cooperating
20 with an arm of said primary lever as a toggle-link which as the mechanism completes the penetrating stroke of the needle approaches and assumes dwell-relations in which its effective length is substantially in line with the center on which said primary lever swings, and a second link which connects the secondary lever with the needle-carrier and which is arranged so that as the mechanism completes the withdrawing
25 stroke of the needle it, the said second link, approaches and assumes dwell-relations in which its effective length is substantially in line with the center on which said secondary lever swings.
